W. W. COREY,
DRAIN VALVE FOR FIRE HYDRANTS,
APPLICATION FILED OCT. 29, 1918.

1,323,351.

Patented Dec. 2, 1919.

Inventor
William W. Corey
By *J. H. Grinnell, Atty.*

UNITED STATES PATENT OFFICE.

WILLIAM W. COREY, OF ST. LOUIS, MISSOURI.

DRAIN-VALVE FOR FIRE-HYDRANTS.

1,323,351.

Specification of Letters Patent.

Patented Dec. 2, 1919.

Application filed October 29, 1918. Serial No. 260,094.

To all whom it may concern:

Be it known that I, WILLIAM W. COREY, a citizen of the United States, residing at St. Louis, Missouri, have invented a certain 5 new and useful Improvement in Drain-Valves for Fire-Hydrants, of which the following is a full, clear, and exact description, such as will enable others skilled in the art to which it appertains to make and use 10 the same, reference being had to the accompanying drawings, forming part of this specification.

My invention relates generally to fire hydrants of the type shown in Letters Patent issued to me, March 12, 1895, No. 535,614, and February 7, 1911, No. 983,268.

The principal object of my invention is to generally improve upon and simplify the construction of certain essential parts 20 of the hydrants disclosed in the patents aforesaid, particularly the drain valve located at the lower end of the stand pipe and the adjustable connection between the adjacent ends of two parts of the valve operating rod, which connection is located at 25 the upper end of the stand pipe.

A further object of my invention is to provide a relatively simple and efficient drain valve housing or barrel which, by 30 virtue of its simple construction, can be easily and cheaply produced, readily applied to or removed from its position of use in the lower end of the stand pipe, and said housing or barrel being provided with a 35 plurality of discharge openings of ample area to permit the rapid escape or drainage of water from the stand pipe and said apertures being disposed so as to minimize the danger of their becoming closed by stones, 40 gravel or earth when the stand pipe is placed in position in the ground.

With the foregoing and other objects in view, my invention consists in certain novel features of construction and arrangement 45 of parts, hereinafter more fully described and claimed, and illustrated in the accompanying drawings, in which—

Figure 1 is an elevational view of a fire hydrant of my improved construction, parts 50 thereof being in vertical section for the purpose of clearly illustrating my improvements.

Fig. 2 is an enlarged vertical section taken 55 through the center of the drain valve barrel and showing the connection between the

drain valve and the lower end of the rod which operates the main valve of the hydrant.

Fig. 3 is an enlarged horizontal section taken approximately on the line 3—3 of 60 Fig. 1.

Fig. 4 is an enlarged horizontal section taken approximately on the line 4—4 of Fig. 2.

Referring by numerals to the accompanying drawings which illustrate a practical embodiment of my invention, 10 designates the stand pipe, 11 the cap on the upper end thereof, 12 the lateral extension near the lower portion of the stand pipe, 13 the valve seat within said lateral extension, 14 the valve which is adapted to rest upon said seat 18, 15 the valve operating rod which extends vertically through the stand pipe, and 16 the connecting links from the valve 14 to the 70 nuts or blocks which are arranged upon the threaded portion of the operating rod 15.

All of the parts just described are well known in the art, and form no part of my present invention.

A cylindrical member 17, preferably of cast metal provides the barrel or housing for the drain valve, said barrel being provided intermediate its ends with a rib or flange 18 which is threaded in order that said barrel may be screw-seated in a suitable aperture formed in the bottom plate of the stand pipe. Formed integral with the lower portion of the body of this barrel and preferably immediately below the flange 18 is a series of 85 externally arranged lugs 19, the same being preferably spaced at equal distances apart, in order to serve as seats or shoulders for a tool such as a spanner wrench which is used in screwing the barrel 17 into the bottom of 90 the stand pipe.

Formed in the inner surface of barrel 17 is a relatively narrow annular slot 20, the depth of which is such that it extends entirely through the wall of said barrel at 100 points between the lugs 19. Thus the open portions 21 of said slot between said lugs 19 constitute drain openings which permit the escape of water from the interior of the drain barrel when the valve within the latter is moved into a position to uncover said openings.

It will be noted that the slot 20 is arranged so that the openings 21 are positioned immediately beneath the shoulder formed by 110

- the lower face of flange 18, and further, that said openings 21 are positioned between the upper portions of lugs 19. Consequently, said openings are to a considerable extent 5 protected by the adjacent parts of the barrel, and the liability of their becoming closed by earth, stones, or the like when the stand pipe is placed in the earth is reduced to a minimum.
- 10 The openings although relatively narrow are of considerable length, and for this reason the combined openings have ample area to permit a comparatively rapid escape of water from the bottom of the stand pipe.
- 15 Formed through the upper portion of the wall of the barrel 17 are openings 22 which permit water to pass from the chamber in the lower portion of the stand pipe into the chamber within said barrel.
- 20 The drain valve which operates within the barrel 17 and controls the openings 21 is in the form of a relatively thick disk 23 of rubber, fiber, or analogous material, said valve being carried by the lower end of a 25 stem 24 which is non-circular in cross section and its upper end being provided with an externally threaded head 25. This head operates within an internally threaded sleeve 26, the latter being secured in any 30 suitable manner to the lower end of the main valve operating rod 15. The lower end of sleeve 26 normally rests on a plate 27, the latter being loosely disposed on top of the drain barrel 17 and being held against 35 rotation by the engagement of its ends with the wall of the stand pipe, this latter arrangement being fully set forth in my Patent No. 983,268.
- 40 The valve stem 24 is arranged to slide freely through a non-circular opening formed in the center of plate 27.
- In the manufacture of the various parts 45 of a hydrant, it very frequently occurs that the upper portion of the body of the stand pipe and the upper portion of the main valve operating rod vary in length and to provide for these inaccuracies, and prevent any lost motion between the upper section of the main valve operating rod and the 50 bearing or socket therefor, I arrange on the upper portion of said main valve operating rod an adjustable collar 28 which is adapted to be locked upon the rod in its adjusted position by a set screw 29, said collar normally bearing against the lower end of a 55 relatively short valve rod operating shaft 30 which latter is mounted for rotation in a suitable bearing or stuffing box 31 in cap 11 and the upper end of said shaft projecting 60 through said cap and provided with a non-circular head 32 adapted to receive a wrench or like tool. The lower end of this short shaft 30 is provided with a recess 33 which is adapted to receive the upper end of valve 65 operating rod 15.

When the parts are assembled, collar 28 is moved upward on rod 15 until it bears against the lower end of short shaft 30 after which set screw 29 is tightened. Thus there is no lost motion between the associated 70 parts and rod 15 cannot move vertically independent of shaft 30.

Under normal conditions or with the main valve 14 closed, as illustrated by dotted lines, Fig. 1, the drain valve 23 occupies 75 a position just below the annular groove 20, as shown in Fig. 2. As shaft 30 and rod 15 are rotated to open main valve 14, sleeve 26 will be rotated, thereby drawing head 25 upward within said sleeve and thus valve 80 23 will be drawn upward into position to close slot 20 and the openings 21. As rod 15 is further rotated to bring valve 14 into full open position, valve 23 and parts 24 and 25 will continue to move upward until said 85 valve 23 occupies a position in the upper portion of the barrel 17, or at a point just below the openings 22. During this movement, stem 24 and parts carried thereby are prevented from rotation by reason of the 90 fact that said stem is non-circular in cross section and occupies a corresponding aperture in plate 27, the latter being held against rotation by engagement with the 95 wall of the stand pipe.

Thus the escape of water through the drain valve is prevented during the time main valve 14 is open and when the latter is closed by proper manipulation of shaft 30 and rod 15, valve 23 will be moved downward to a point below groove 20 and openings 21 and the water from the chamber within the stand pipe is now free to pass through apertures 22 to the chamber within barrel 17 and from thence outwardly 100 through openings 21 and thus drain into the ground adjacent to the lower end of the stand pipe.

To protect that portion of the drain valve 110 housing or barrel which projects below the bottom plate of the stand pipe, I prefer to form integral with the lower end of the stand pipe an annular wall or depending flange A which is spaced apart from and surrounds the depending portion of said 115 barrel.

A drain valve of my improved construction can be easily and cheaply manufactured, can be readily applied to or removed from the stand pipe, is quick-draining by 120 reason of the relatively large area of the combined drain openings and said drain openings occupy positions in the barrel of the drain valve where they are afforded a maximum degree of protection against being 125 closed by gravel, dirt or the like.

It will be readily understood that minor changes in the size, form and construction of the various parts of my improved drain valve may be made and substituted for those 130

herein shown and described, without departing from the spirit of my invention, the scope of which is set forth in the appended claims.

5 I claim:

1. In a fire hydrant, a drain valve comprising a substantially cylindrical housing adapted to be removably positioned in the lower portion of the stand pipe of the hydrant, a continuous horizontally disposed drain opening formed through the wall of the valve housing, lugs externally arranged on said housing and bridging said drain opening, and a valve arranged to move vertically within said housing and adapted to close said drain opening. 10
2. In a fire hydrant, a drain valve comprising a substantially cylindrical housing adapted to be removably positioned in the lower portion of the stand pipe of the hydrant, a continuous horizontally disposed drain opening formed through the wall of the valve housing, lugs externally arranged on said housing and bridging said drain opening, a valve arranged to move vertically within said housing and adapted to close said drain opening, and connections from said valve to the operating rod for the main valve of the hydrant. 15
3. In a fire hydrant, a drain valve comprising a substantially cylindrical member, an externally arranged rib formed on said member, the outer face of which rib is threaded whereby said member may be screw-seated in the lower portion of the stand pipe of the hydrant, there being an annular slot formed through the wall of said cylindrical member immediately below the threaded rib, and integrally formed lugs on said cylindrical member immediately below the threaded rib, which lugs bridge the annular slot and form a connection between the upper and lower portions of said cylindrical member. 20
4. In a fire hydrant, a drain valve comprising a substantially cylindrical housing adapted to be removably positioned in the lower portion of the stand pipe of the hydrant, said housing being provided with an internally arranged annular slot, portions of which are extended entirely through the wall of the housing to form elongated relatively narrow drain openings, external lugs on the housing between said drain openings, and a valve arranged for vertical movement within said housing. 25
5. A drain valve for fire hydrants and the like comprising a substantially cylindrical housing having an externally arranged threaded rib whereby said housing may be screw-seated in the lower portion of the stand pipe of the hydrant, lugs on said housing beneath said rib, there being relatively narrow elongated drain openings formed through the wall of the housing be- 30
6. A drain valve for fire hydrants and the like comprising a substantially cylindrical housing having an externally arranged threaded rib whereby said housing may be screw-seated in the lower portion of the stand pipe of the hydrant, lugs on said housing beneath said rib, there being relatively narrow elongated drain openings formed through the wall of the housing between said lugs and beneath said rib, there being inlet openings formed through the upper portion of the wall of said housing; and a valve arranged for movement within said housing and adapted to close said openings. 35
7. A drain valve housing for fire hydrants comprising a substantially cylindrical member provided with an internally arranged annular groove, and there being relatively narrow elongated openings formed through the wall of the housing and communicating with said groove. 40
8. A drain valve housing for fire hydrants comprising a substantially cylindrical member provided with an internally arranged annular groove, there being relatively narrow elongated openings formed through the wall of the housing and communicating with said groove, and externally arranged lugs on said housing between said openings. 45
9. A drain valve housing for fire hydrants comprising a substantially cylindrical member provided with an internally arranged annular groove, there being relatively narrow elongated openings formed through the wall of the housing and communicating with said groove, and there being a shoulder formed on the outer surface of said housing immediately above said openings. 50
10. A drain valve housing for fire hydrants comprising a substantially cylindrical member provided with an internally arranged annular groove, there being relatively narrow elongated openings formed through the wall of the housing and communicating with said groove, externally arranged lugs on said housing between said openings, and there being a shoulder formed on the outer surface of said housing immediately above said openings. 55
11. A drain valve for fire hydrants comprising a substantially cylindrical member, externally arranged lugs on the lower portion of said member, which lugs are spaced apart to form a seat for a spanner wrench, and there being an annular slot formed entirely through the wall of said cylindrical member in the same plane with said lugs, the portions of said slot between said lugs constituting drain openings. 60
12. A drain valve for fire hydrants comprising a substantially cylindrical member, externally arranged lugs on the lower por- 65

- tion of said member, which lugs are spaced apart to form a seat for a spanner wrench, there being an annular slot formed entirely through the wall of said cylindrical member 5 in the same plane with said lugs, the portions of said slot between said lugs constituting drain openings, and an externally threaded rib formed on the cylindrical member immediately above said lugs.
- 10 13. A drain valve for fire hydrants comprising a substantially cylindrical member, externally arranged lugs on the lower portion of said member, which lugs are spaced apart to form a seat for a spanner wrench,

there being an annular slot formed entirely 15 through the wall of said cylindrical member in the same plane with said lugs, the portions of said slot between said lugs constituting drain openings, an externally threaded rib formed on the cylindrical member immediately 20 above said lugs, the upper end of said cylindrical member being provided with a valve seat, and there being water inlet openings formed through the upper portion of the wall of said cylindrical member.

In testimony whereof I hereunto affix my signature, this 26th day of October, 1918.

WILLIAM W. COREY.
